UNITED STATES PATENT OFFICE.

CHARLES F. MITCHELL, OF SOMERSET, KENTUCKY.

RAIL BRACE OR CLAMP.

1,189,157.

Specification of Letters Patent. Patented June 27, 1916.

Application filed December 28, 1915. Serial No. 69,059.

To all whom it may concern:

Be it known that I, CHARLES F. MITCHELL, a citizen of the United States, residing at Somerset, in the county of Pulaski and State 5 of Kentucky, have invented certain new and useful Improvements in Rail Braces or Clamps, of which the following is a specification, reference being had therein to the accompanying drawing.

10 This invention relates to an attachment for rails, and while susceptible of a variety of uses, is more especially adapted for connecting adjacent or abutting ends of rail sections whereby to prevent relative lateral 15 movement of the rail sections, and overcoming to a large extent, the relative creeping tendency of said rail sections.

Many efforts have heretofore been made to provide an attachment or joint of the 20 character just mentioned, which would answer the necessary requirements, but a large majority of these, with which I am familiar, have not proven entirely satisfactory or practicable, for various reasons, among which 25 may be mentioned the complicated character thereof, the expense incident to manufacture, application and upkeep, the inefficient bracing and holding characteristics, the necessity of drilling or otherwise weakening 30 the rail sections due to the application of the device, the loosening of the joint and resultant spreading of the rail sections in use, the large number of bolts required, and separation and loss of the latter, etc.

35 It is one of the primary objects of the present invention, to overcome the above and other existing objections or defects in rail joints and allied devices as at present constructed, and to this end, I provide a 40 novel and improved type of construction, involving but a few parts, comparatively simple and inexpensive to produce, readily applicable to and detachable from the rail sections, and highly efficient, satisfactory and 45 durable in use.

Another important feature of the invention, resides in the provision of coöoperating rail engaging members to engage at opposite sides of the rail sections, and novel means 50 for securing said members in holding contact with the rail sections, without the necessity of providing holes in, or otherwise damaging, the rail sections, as would be the result of direct application thereto of the retaining 55 means for the engaging members.

The present invention is of peculiar and especial advantage and usefulness for emergency repair purposes when split rails are encountered, since the device is readily applicable to rails of standard construction 60 without preliminary drilling or altering the construction of rail sections in any particular, and when so applied, the severed sections of the rail are firmly supported, braced and maintained against lateral separation. 65

Still another feature of the invention, resides in the provision of means whereby the coöoperating members of the brace or joint constitute a reinforced or supporting medium for one another, thereby taking considerable strain from the rail sections themselves, and in carrying out this feature of the invention, the coöoperating joint members preferably are arranged to contact at the base, whereby to constitute a fulcrum at 70 this point in the action of the interposed securing means in drawing the clamping portions of the joint members in binding contact with the rail sections.

Other improvements, and novel details in 80 the construction and arrangement of parts will be appreciated from the description to follow, when considered in connection with the accompanying drawings, which form a part hereof, and wherein is disclosed for the 85 purpose of illustration, a convenient and satisfactory embodiment of the invention.

In the drawings:—Figure 1 is a side elevation of adjacent rail sections with my improvements applied. Fig. 2 is a top plan 90 of the same. Fig. 3 is a cross section substantially on the line 3—3 of Fig. 1 looking in the direction of the arrows. Fig. 4 is a cross section substantially on the line 4—4 of Fig. 1, looking in the direction of the 95 arrows.

With more particular reference to the drawings, wherein like reference numerals refer to corresponding parts throughout the several views, A and B represent respectively 100 rail sections adapted to be connected, and C rail ties of usual construction projecting beneath opposite rails and supporting the latter. The rail sections A may be of any approved type or standard construction comprising a head or tread part 1, a base 2, and vertical connecting web 3. The upper surface of the base 2, is tapered downwardly in opposite directions from the web part 3 as indicated at 2^a, and the undersurface of the 110

tread portion has the usual taper or incline upwardly and outwardly from the web as indicated at 1^a.

The means herein contemplated for connecting adjacent rail sections together is preferably of the following construction, it being observed in this connection however that minor changes in details and construction of parts may be resorted to and still be within the spirit of the invention. The connecting means or joint for the rail sections includes coöperating members and as these members are substantially duplicates of one another, a description of one will suffice for the other. 4 is an elongated base part preferably of a length to underlie a considerable portion of adjacent rail sections, and of a width to terminate short of the center of the base 2 of the rail, whereby when the coöperating members are in place the respective base members 4 will be slightly spaced from one another at the adjacent edges as indicated at 4^a. Connecting with the base part 4 at the outer edge thereof and at a point beyond the side edge of the base 2 of the rail, is a vertical extension 5 overlying the edge of the base 2 and connecting with an upwardly and inwardly directed flange 6 overlying the inclined portion 2^a of the base of the rail section and in turn connecting with a vertically extending clamping part 7 of a height to substantially fill the space between the undersurface 1^a of the tread portion 1 and the upper surface 2^a of the base portion 2, of the rail section. It will be observed from a reference to Fig. 4, which illustrates more particularly the application of the coöperating joint members previous to being moved to clamping position, that the clamping portion 7 tapers inwardly toward the upper end thereof and contacts with the rail section only at the points 7^a and 7^b thereof, which said contact points of the clamping members are rounded, as is also the inner lower edge 7^c of the clamping portion 7. Except at the points 7^a and 7^b and the upper surface of the base part 4, the clamping members in the application of the same are spaced from the rail sections for a purpose to be hereinafter more particularly described. The clamping members are preferably formed of steel whereby to have certain resilient properties and the base portion 6 is preferably of less thickness than the vertical portion 5, and clamping member 7. Also the clamping member 7 is provided preferably at its inner face with a recess or cut-out part 7^d whereby to provide for sufficient spring or yieldability of the member 7 in the seating of the same.

The means for forcing the clamping member 7 into holding engagement with the rail sections is preferably of a character making unnecessary any drilling or otherwise altering the construction of the rail, and this

means in the preferred embodiment of the invention is constructed substantially as follows:—8 is a base extension or lug projecting downwardly from the base part 4 at a point substantially midway of the ends of the base part 4 and adapted to be positioned in the space between the tie members C as illustrated more particularly in Figs. 1 and 2 of the drawing. The lug 8 has a straight outer surface 8^a which constitutes in effect, a continuation of the vertical flange 5, whereas the inner surface of the lug 8, has a portion 8^b tapering inwardly from a contact or abutment point 8^c to the top, which said top edge of the inner surface is preferably curved as indicated at 8^d. Said inner surface of the lug 8 is also curved at the lower edge as indicated at 8^e.

Securing means for the lugs 8 preferably take the form of bolts 9, two being ordinarily sufficient to answer the requirements, and the same extending in opposite directions, that is to say the headed end 9^a of one bolt will be disposed to contact the outer surface of one lug whereas the headed end 9^a of the coöperating bolt will be disposed to contact the outer surface of the coöperating lug. The bolts have a flattened portion 9^b, and the lugs are provided with suitable apertures extending therethrough adapted to conform with the shape of the bolts, whereby the flattened portion of the bolts which fits in a recessed part corresponding therewith, will prevent turning movement of the bolts in said apertures. It will be understood that the receiving apertures in the lugs 8 for the bolts 9 are of a diameter somewhat greater than that of the bolts 9 whereby to allow sufficient play for the movement of the clamping members in the seating of the latter. Suitable nuts 10 are adapted to engage the threaded ends of the bolts 9 and interposed between the nuts 10 and the outer surface of the lugs 8, is a suitable lock washer 11 of any desired type.

The operation of the device may be reviewed as follows:—It being assumed that the coöperating members of the joints are applied as indicated more particularly in Fig. 4 to rail sections to be united. It will be observed that so soon as the nuts are rotated the abutting portions 8^c of the lugs 8 will be brought into contact, and thereafter the points 8^c constitute bearings or fulcrums for the coöperating members, the portions 5, 6 and 7 of which members in the further movement of the nuts will be forced inwardly into tight clamping position as illustrated more particularly in Fig. 3 of the drawings. The yieldable character of the metal employed, together with the particular construction of the member 9 permits of sufficient spring to obtain the clamping action just referred to.

By reason of the fact that the coöperat-

ing members of the joint or brace are substantially duplicates of one another, it will be appreciated that they are reversible and readily applicable to either side of the rail, 5 and it will also be appreciated that because of the opposed disposition of the bolts, the binding action of the bolts on the coöperating members on the joint is equalized. It is also to be observed that as distinguished 10 from many joints now in use, there is no tendency for the clamping members 7 to become loosened from clamping position, but on the contrary the weight of the cars in traveling over the rail will tend to increase 15 the clamping characteristics of the members 7 due to the resistance of the bolts and coöperating abutment heels 8. The various parts are so proportioned that the parts 6 and 7 must not come in contact with the rail until the bolts are sufficiently tightened 20 to bring said parts snugly against the rail on both sides. When the clamping members are sprung or forced home in the manner described they will be found to grip 25 the web part of the rail as well as the base thereof.

While the device is an exceedingly simple one, readily applicable, at the same time, the same will be found to be exceedingly 30 rigid and durable in use and a great time saver in emergency repairs, owing to the fact that the securing bolts 9 are positioned below the rail, and it is not necessary to drill or otherwise alter the construction of 35 the rail in the application.

Suitable anchoring means for the clamping members preferably take the form of spikes 12 of any desirable construction adapted to engage in recessed lugs 13 projecting 40 outwardly from the base members 4 as illustrated more particularly in Figs. 1 and 2. Said spikes serve to anchor the clamping members to the tie members C as is obvious.

45 What I claim is:—

1. In a device of the character described, the combination of coöperating clamping members having relatively thin portions to engage in the space between the tread and base of a rail and having a base part to underlie the base of the rail, said base part having downwardly projecting relatively thick lugs adapted to contact with one another adjacent the bottom thereof, and separated 50 from one another above said contacting point, securing bolts connecting said lugs, and that portion of the clamping members to engage in the space between the tread and base of the rail being of yieldable metal and free from connection whereby the same is forced into binding position by the securing of the bolts.

2. In a device of the character described, the combination of opposing clamping members 55 to engage opposite sides of a rail be-

tween the tread and base thereof and having a cut-out part in the rail engaging surfaces thereof, said clamping members being of yieldable metal, and means connecting the clamping members at points below the rail to spring 70 said clamping members into binding contact with the rail.

3. In a device of the character described, the combination of opposing clamping members to engage opposite sides of a rail between the tread and base thereof, said clamping members being of yieldable metal, means connecting the clamping members at points below the rail to spring 75 said clamping members into binding contact with the sides, head and base of the rail, said means including headed bolts extending in opposite directions through the clamping members, and nuts engaging threaded ends of said bolts, and said clamping members being unconnected at points 80 above the base of the rail.

4. In a device of the character described, the combination of coöperating clamping members adapted to engage in the space between the head and base of a rail and at any point throughout the length of the rail, said clamping members having a recessed part opposite the web of the rail and also having parts underlying the base of the 95 rail, and means positioned entirely below the web of the rail for engaging said underlying parts to force the clamping members in holding engagement with the rail.

5. In a device of the character described, 100 the combination of opposed clamping members of a height to substantially fill the space between the head and base of a rail, said members being of yieldable metal and having a cut-out weakened part disposed 105 opposite the web of the rail and parts to underlie the base of the rail, said underlying parts of the clamping member having downwardly projecting lugs of substantially the width of the rail adapted to contact for a 110 substantial distance upwardly from the base thereof and tapering inwardly from said contacting parts, and means engaging said underlying parts to force the clamping members into binding contact with the rail. 115

6. In a device of the character described, the combination of opposed clamping members comprising vertically extending portions of a height to substantially fill the space between the head and base of rail sections, and portions to extend over the top of the base of the rail and under the base of the rail, the underlying portions of the respective clamping members being separated from one another, and downwardly 120 projecting lugs, said lugs having an extended bearing surface from a point adjacent the base thereof upwardly whereby the bearing surfaces of the clamping members constitute a fulcrum, and said lugs when in con- 125

tact being of a width projecting outwardly beyond the edges of the base of the rail, and connecting bolts projecting between said lugs at a point adjacent the base of the 5 rails and above said bearing portions, and adapted to force the vertically projecting portions of the clamping members into wedging contact with the sides, top and base of the rail.

10 7. In a device of the character described, the combination of opposed clamping members, each of said members comprising a relatively thin portion to engage in the space between the top and base of the rail 15 and having an intermediate cut-out part opposite the web of the rail intermediate the top and bottom thereof, said relatively thin portions connecting with thickened portions engaging over the top of the base of the 20 rail and under said base of the rail, and lugs projecting downwardly from the underlying portions of the clamping members, said lugs having a vertically extended bearing surface at the inner edge thereof, the lugs being spaced from one another above said bearing surfaces, and means for forcing the 25 clamping members in wedging contact with the top, web and base of the rail, said means comprising connecting bolts projecting through said lugs at a point adjacent the 30 base of the rail.

8. In a device of the character described, the combination of opposed clamping members to engage in the space between the top

and base of a rail and having thickened 35 portions to engage the web of the rail at points of connection of the web with the head and base of the rail and an intermediate portion of reduced thickness, and means beneath the rail for connecting the clamping members and maintaining the same in wedging engagement with the rail.

9. In a device of the character described, the combination of opposed clamping members to engage opposite sides of a rail between the head and base thereof, said clamping members having vertically extending parts projecting over the edges of the base of the rail, and horizontally extending parts projecting beneath the rail and downwardly 50 projecting lugs substantially midway of the ends of the clamping members, said lugs having a straight outer surface constituting in effect a continuation of the vertical flanges, and the inner surfaces of the lugs 55 having a portion tapering inwardly from an extended fulcrum or bearing point adjacent the base thereof, said inner surfaces of said lugs being curved at the base thereof, and bolts connecting said lugs, the clamping 60 members being otherwise free from connection.

In testimony whereof I hereunto affix my signature in the presence of two witnesses.

CHARLES F. MITCHELL.
